United States Patent Office.

MARY A. LAURENCE, OF NEW YORK, N. Y.

Design No. 2,572, dated February 12, 1867.

DESIGN FOR AN ORNAMENT FOR HATS AND DRESSES.

The Schedule referred to in these Letters Patent and making part of the same.

TO ALL WHOM IT MAY CONCERN:

Be it known that I, MARY A. LAURENCE, of the city of New York, in the county of New York, and State of New York, have originated and designed an Ornament suitable for ladies' bonnets, dresses, mantillas, neck-ties, and general purposes, of which the following is a full, clear, and exact description, reference being had to the accompanying drawings, making part of this specification.

Figure 1 on the diagram: first, the back, neck, and head of the bird are cut out of the silk in one piece; second, the breast is a separate piece, joined on or sewed on to the above with needle and thread; the body is then turned, stuffed with zephyr, worsted, or any other suitable material; third, the beak, which is a thorn of a bush or tree, or any other article suitable for the purpose, is fastened into the head with needle and sewing-silk or thread; fourth, the eyes are composed of small beads, and are inserted with needle and thread; fifth, the tail is made of stiff paper or card covered with silk material the same as the body, which is sewed on the body of the bird; sixth, the body and entire bird are then embroidered on the head and tail with sewing-silk, then ornamented with beads or bugles, as shown; seventh, the wings are made of the same material and in the same manner as the tail, which, after being embroidered and ornamented with beads and bugles, are sewed on the body of the bird; eighth, the bird is then wired with ribbon wire (fine); ninth, the fringe is composed of beads and bugles, and ornamented with dew-drops.

Figure 2 shows the same design in a closed or folded condition as represented in fig. 1 in an expanded condition.

What I claim as my invention, and desire to secure by Letters Patent, is—

The design or pattern for an ornament suitable for ladies' bonnets, dresses, mantillas, neck-ties, and general purposes, herein set forth and shown.
